ADJUSTABLE HANGER

James Speranza, Wilmerding, Pa.

Application January 30, 1939, Serial No. 253,702

3 Claims. (Cl. 248—263)

My invention relates to improvements in combination shade and curtain holders.

An important object of my invention is to provide a device adapted to be easily and expeditiously applied to window frames of varying widths.

Another object of my invention is to provide a device that will stay securely in place when once installed, and remain in an operative position until manually removed.

Yet another object of my invention is the provision of a device that will effectively support curtains and drapes in association with the roller thereof.

Still another object of my invention is the provision of a combination shade and curtain holder that is simple in construction, efficient in operation, and inexpensive to manufacture.

Other objects and advantages of my invention will be apparent during the course of the following description.

In the drawings, forming a part of this specification, and in which like numerals are employed to designate like parts throughout the same,

Figure 1 is a top plan view of a device embodying my invention,

Figure 2 is a front elevation of the same,

Figure 3 is a top plan view of my device and showing parts broken away,

Figure 4 is a perspective view of the window frame engaging bracket,

Figure 5 is a fragmentary view, partly in elevation and partly in section, illustrating the curtain holding bracket,

Figure 6 is a fragmentary sectional view, illustrating another form of my invention,

Figure 7 is a front elevation of the same,

Figure 8 is a perspective view of the window frame engaging bracket embodied by the second form of my invention,

Figure 9 is a vertical sectional view taken on the line 9—9 of Figure 8,

Figure 10 is a view similar to Figure 9 illustrating the teeth as pointed instead of wedge shaped, and

Figure 11 is a perspective view of another form of window bracket.

In the accompanying drawings, wherein for the purpose of illustration, are shown preferred embodiments of my invention, the numeral 10 designates a tubular element having a ferrule 11 positioned on the end 12 and receiving the set screw 13 adapted to hold the window frame engaging bracket 14 slidably adjusted therein.

55 A similar bracket 15 is slidably adjustable within

the opposite end 16 of the tubular member 10. The brackets 14 and 15 are formed with rearwardly projecting shanks 17 having inwardly bent teeth 18 adapted to engage a window frame 19. The portion of the brackets extending forwardly of the tube 10 is bifurcated, and each bifurcation thereof forms a continuation of the shank 17. The top edge 21 of the bifurcation 20 is provided with a plurality of spaced slots 22 adapted to receive the ends of the straight, adjustable curtain rods 23, and the extremity 24 thereof is adapted to receive a U-shaped curtain rod 25. The lower bifurcation 26 extends in spaced parallelism to the bifurcation 20, and the extremity 27 thereof is adapted to permit the conventional U-shaped adjustable curtain rod 29 to be fitted thereon. The extremity 27 terminates a substantial distance from the shank 20 so that the curtain rod 29 will be suitably spaced away from the outer rod 25. Pendent straps 30 are formed integrally with the brackets 14 and 15 at approximately their middle and the ends 31 thereof are bent inwardly at right angles thereto. The shade brackets 33 are formed with a longitudinally extending portion 34 having an elongated slot 35 formed therein which receives the bolt 36. The head of the bolt 36 is of greater diameter than the slot 35, and will permit the bracket 33 to be slidably adjusted on the end 31 of the strap 30. The end 37 of the bracket 33 is bent outwardly at right angles to the end portion 34 and is provided with an opening 38 adapted to receive the ends of the shade 32 therein.

Projecting inwardly from the brackets 14 and 15 are tubular portions 39 and 40 slidably mounted within the tubular member 10. The tubular portion 39 of the bracket 14 is longitudinally adjustable within the end 12 of the tube 10 and maintained in the desired position by the set screw 13. The tubular portion 40 of the shank 15 is provided with a disk member 41 securely positioned in its end, and a disk 42 is secured by means of the bolt 43 within the tubular member 10 a substantial distance inwardly from the disk 41. Interposed between the disks 41 and 42 is a retractile spring 44 each end of which is secured to the disks 41 and 42 by means of the bolts 45 and 46.

From the above description it will be noted that the bracket 14 may be adjusted longitudinally of the tubular member 10 and held in the desired position by means of the set screw 13. For the best operation of my device, the distance between the teeth 18 of the brackets should

be slightly less than the distance between the outer edges of the frames 19 of the window, so that when the bracket 15 is pulled outwardly against the action of the spring 44 the resilient action of the said spring will be sufficient to cause the teeth 18 to bite into the outer edge of the frame 19, and the continued pull of the spring will be sufficient to maintain the teeth 18 securely imbedded in the frame in a manner to prevent the same from being accidentally displaced therefrom.

The straight adjustable curtain rods 23 may be positioned in one or both of the grooves 22 of the shanks 20 and may be used to hold curtains, or the like, in proper association with the window. The outer U-shaped adjustable curtain rods 25 and 29 may be positioned on the ends of the bifurcations 20 and 26 and are adapted to permit the hanging of drapes, or the like, about the window.

The form of my invention, as illustrated in Figures 6, 7 and 8 is substantially the same as the first form except that the teeth 18 of the brackets 14 and 15 are bent outwardly and the spring 47 is a compression spring, so that when the teeth 18 are adjusted with respect to the frame 19 in a manner whereby the distance between the teeth 18 is slightly greater than the distance between the inner edges of the frame, the bracket 15 can be compressed against the action of the spring 47, and the teeth 18 imbedded in the inner edge of the frame. The action of the spring 47 will be sufficiently great to cause the teeth to be firmly imbedded in the inner edge of the frame, and to hold the same against casual displacement. The teeth 18 may be wedge shaped as illustrated in Figure 9 or if desired they may be made pointed as illustrated in Figure 10.

The shade receiving brackets 33 are adjustable so that regardless of the adjustments made between the tubular member 10 and the brackets 14 and 15 the shade receiving brackets may be adjusted relative thereto in a manner to properly position the shade. In Figure 11, however, I have shown a form of shade receiving bracket that is not adjustable but which it may be desirable to use at certain times. In this form the numeral 48 designates a shank extending rearwardly of the shank 26 and in spaced parallel relation with the shank 17. The shank 48 is bent inwardly at right angles to the shank 17 and back upon itself to form a U-shaped bracket extending inwardly from the plane of the brackets 14 and 15. An opening 49 is provided in the inner flange of the U-shaped shank 48 to receive the end of the shade 32.

It is to be understood that the form of my in-

vention herewith shown and described is to be taken as a preferred example of the same and that the various changes in the size, shape, and arrangement of parts may be resorted to without departing from the spirit of my invention, or the scope of the appended claims.

Having thus described my invention, I claim:

1. A bracket for curtain and shade fixtures comprising an attaching arm secured at one end to a transversely disposed plate member extending at opposite sides and below the arm, said plate member terminating at one side of the arm in angularly bent tooth elements, and the portion thereof at the opposite side of the arm being bifurcated to define upper and lower prong elements, the upper prong having spaced notches adapted to receive curtain rods and both the upper and lower prongs being shaped to slidably accommodate drape rods, the portion of the plate below the arm being bent inwardly below the arm and adapted to support a curtain roller.

2. A bracket for curtain and shade fixtures comprising an attaching arm secured at one end to a transversely disposed plate member extending at opposite sides and below the arm, said plate member terminating at one side of the arm in angularly bent tooth elements, and the portion thereof at the opposite side of the arm being bifurcated to define upper and lower prong elements, the upper prong having spaced notches adapted to receive curtain rods and both the upper and lower prongs being shaped to slidably accommodate drape rods, the portion of the plate below the arm being bent angularly in spaced parallel relation with the arm and longitudinally slotted; and a curtain roller bracket slidably associated with the last-mentioned portion of the plate.

3. A bracket for curtain and shade fixtures of the type adapted to have a spring influenced adjustable association with a tubular connecting member, comprising an attaching arm connected at one end to a transverse plate portion extending laterally of the arm, the portions of the plate at opposite sides of the arm being bifurcated, the upper bifurcation at one side of the arm terminating in angularly disposed holding prongs and the bifurcation therebelow being bent upon itself to define a resilient spring arm, said arm having an opening adapted to receive a curtain roller, the upper bifurcation at the other side of the arm being crenelated to receive curtain rods and both the upper and lower bifurcations being shaped to slidably receive a telescoping type of drape rod.

JAMES SPERANZA.
